FIRE EXTINGUISHER DISCHARGE APPARATUS

Hilding V. Williamson, Chicago, Ill., assignor, by mesne assignments, to Reconstruction Finance Corporation, Chicago, Ill., a corporation of the United States

Application September 28, 1942, Serial No. 460,010

12 Claims. (Cl. 299—79)

This invention relates to new and useful improvements in fire extinguisher discharge apparatus and deals more specifically with the discharge of high pressure extinguishers, such as carbon dioxide, through hose lines of substantial length.

Carbon dioxide, when employed as a fire extinguishing medium, is usually confined as a liquid in either relatively small bottles or cylinders, at the uncontrolled temperature of the surrounding atmosphere, or in large capacity, bulk storage tanks, at a controlled, substantially constant, subatmospheric temperature of any desired value. Confined liquid carbon dioxide possesses a fixed vapor pressure value for every temperature value. These corresponding temperature and pressure values may be illustrated by pointing out that a normal temperature range for the liquid confined in bottles or cylinders is from 60° F. to 87.8° F. and the corresponding pressure range is from 748.6 to 1066.2 pounds per square inch, absolute, while the controlled subatmospheric temperature most frequently selected for the liquid confined in bulk storage tanks is 0° F., which provides a corresponding vapor pressure of approximately 305 pounds per square inch, absolute.

It will be appreciated, therefore, that carbon dioxide in the forms in which it is normally employed as a fire extinguishing medium, possesses such a high vapor pressure that it is not desirable to subject hose lines to the same for any longer period of time than is absolutely necessary. For example, it would be very destructive to a hose line to maintain it at all times in open communication with the storage space of the liquid carbon dioxide and rely solely on a valve at the outer end of the hose line for controlling the periods of discharge. Furthermore, if the hose line is of substantial length and is normally wound on a reel, a rotatable joint must be employed at some point between the reel and the fixed supply pipe for the extinguishing medium. A difficult maintenance problem is presented if it is necessary to keep such a joint leak proof while constantly subjecting the same to the three hundred, or more, pounds per square inch pressure of the liquid carbon dioxide for an indefinite length of time.

It would appear to be a very simple matter to solve the above noted difficulties by merely providing a manual valve in the supply pipe in advance of the rotary joint for the hose reel and opening this valve before placing the hose line

in service. The use of such a manual valve is entirely satisfactory if the party that handles the hose line remembers, at such an exciting time, to open the valve before running out the fifty to one hundred feet of line that is usually wound on a reel; or, failing to remember, if the discharge end of the hose line is provided with a second valve which is in a fully operative condition and which has not been left open by the operator while he returns to the location of the reel to open the main valve.

Carbon dioxide is an extremely effective fire extinguishing medium but its use is subject to one limitation which must be constantly kept in mind at all times while designing equipment and while planning installations to protect certain hazards. This limitation is that the initial cost of portable equipment and fixed installations is directly proportionate to the amount of carbon dioxide made available for use. Therefore, the quantity of carbon dioxide made available for protecting any given hazard seldom exceeds, by any substantial amount, the quantity that is calculated as being sufficient to effect extinguishment if the equipment is handled and operates properly. In other words, carbon dioxide is never made available in such unlimited amounts as water.

The longer a fire burns, the more it is likely to spread and the higher the temperature of the involved materials and surrounding objects. As it requires a certain amount of carbon dioxide, properly applied, to extinguish a fire of a given size and intensity, or temperature, the time lost by an operator in traveling back and forth between the nozzle end of the hose line and a valve at the reel may mean the difference between a sufficient and an insufficient amount of carbon dioxide to effect complete extinguishment. In any event, such a procedure creates considerable excitement and confusion at a time when cool thinking and deliberate action are essential.

If carbon dioxide, confined at a vapor pressure of several hundred pounds per square inch, is discharged from the end of a hose line which is not firmly held by at least one rather stocky individual, the hose with its heavy discharge nozzle will whip and thrash around in such a violent manner as to be likely to cause serious injury to anyone trying to recapture the same. Also considerable valuable time and carbon dioxide will be lost. It is apparent, therefore, that need for the operator of a carbon dioxide hose

line to return to a main valve, located at the hose reel, to open the same after the hose has been run out may have disastrous results.

It is the primary object of this invention to provide a hose line type of discharge apparatus for high pressure fire extinguishing liquids in which the hose line will not be subject to the pressure of the liquid except when in actual service, and in which the operator will be prevented from removing the hose line and its discharge nozzle from the carrier mechanism without first placing the hose line in communication with the source of supply of the extinguishing medium.

A further important object of the invention is to provide holding means for the discharge nozzle of a hose line which must be manipulated to release the nozzle for use and to replace the nozzle after use, and wherein such manipulations of the holding means will result in turning on and off the supply of fire extinguishing medium to the hose line.

Other objects and advantages of the invention will be apparent during the course of the following description.

In the accompanying drawings forming a part of this specification and in which like numerals are employed to designate like parts throughout the same,

Figure 1 is a side elevational view of fire extinguishing apparatus including a hose line wound on a reel, supporting and holding means for the discharge nozzle at the outer end of the hose line, and valve mechanism for controlling the delivery of the extinguishing medium to the hose line,

Figure 2 is an elevational view of the mechanism shown in Fig. 1 and taken at right angles to this latter figure,

Figure 3 is a detail front elevational view of the holding mechanism for the hose line discharge nozzle and pilot valve mechanism which is associated therewith,

Figure 4 is a detail top plan view of the structure shown in Fig. 3,

Figure 5 is a longitudinal sectional view of a portion of the "play-pipe," which connects the discharge nozzle to the outer end of the hose line, and the control valve that is incorporated in said "play-pipe,"

Figure 6 is a longitudinal sectional view of the pressure controlled and operated main valve which functions to control the flow of the extinguishing medium to the hose line,

Figure 7 is a detail elevational view of the pilot valve structure which is associated with the hose line nozzle holding mechanism of Figs. 3 and 4, and

Figure 8 is a sectional view of the pilot valve, taken on line 8—8 of Fig. 7.

In the drawings, wherein for the purpose of illustration is shown the preferred embodiment of this invention, and first particularly referring to Figs. 1 and 2, the reference character 10 is employed for designating the spaced mounting members for the hose reel 11. The mounting members 10 are provided with suitable bearings 12 for journaling the combined reel shaft and supply pipe section 13.

A suitable length of hose line 14 is properly connected at its inner end to the formed pipe 14a which in turn is connected to the pipe section 13. The laterally projecting end portion of this pipe section is connected by a swivel or rotary joint 15 to the supply pipe 16. This supply pipe may include any desired couplings, etc., to properly

associate the same with the mounting of the hose reel 11 and the location of the source of supply of the fire extinguishing medium, such as liquid carbon dioxide, which is under a considerable pressure head. A main control valve 17 is coupled in the supply pipe 16 and functions to control the supply of the extinguishing medium to the hose line 14.

Suitably coupled to the outer end of the hose line 14, as at 18, is a "play-pipe" 19 which has suitably connected to its outer end the discharge nozzle 20. The "play-pipe" 19 is formed of two rigid metal pipe sections which are covered with suitable insulation so that they may be safely held in the hands of the operator, to enable him to direct the discharge of low temperature carbon dioxide from the nozzle 20. A secondary control valve 21 is suitably connected to the adjacent ends of the two sections of the "play-pipe" 19 and is intended to be manually operated to control the discharge of the extinguishing medium from the nozzle 20.

A suitable nozzle supporting platform or shelf 22 is arranged relative to the hose reel 11 to accommodate the nozzle 20 in the manner clearly illustrated in Figs. 1 and 2. For the purpose of retaining the discharge nozzle 20 and the "play-pipe" 19 in its intended position with respect to the platform or shelf 22, a holding device 23 is provided. This holding device 23 must be manipulated to release the discharge nozzle and its "play-pipe" so that the hose line 14 may be run out or pulled off of the reel 11 when the apparatus is to be used to extinguish a fire. The holding mechanism, also, must be manipulated to secure the discharge nozzle 20 and "play-pipe" 19 in their intended positions with respect to the supporting platform or shelf 22 when the hose line 14 is returned to the reel 11 after use of the apparatus.

The manipulation of the holding mechanism 23 to release and secure the discharge nozzle 20 and "play-pipe" 19 result in operating a pilot valve 24. This pilot valve is connected to the vapor or liquid supply tubing 25 and the vapor or liquid pressure delivery tubing 26. This latter tubing extends to the main control valve 17.

The above description outlines in a general way the principal instrumentalities which are incorporated in this fire extinguishing discharge apparatus. When it is desired to employ the hose line apparatus to extinguish a fire, the nozzle holding mechanism 23 is manipulated to release the nozzle, and its "play-pipe" so that the hose line can be pulled off of the reel 11. This manipulation of the holding mechanism 23 results in operating the pilot valve 24 for venting to the atmosphere the vapor or fluid pressure which is normally maintained in the length of tubing 26. The venting of the vapor or fluid pressure from this tubing results in opening of the main control valve 17 so that the fire extinguishing medium will flow into the hose line 14 in readiness for use when the operator of the nozzle reaches the scene of the fire. The fire extinguishing medium will not be discharged from the nozzle 20 until the operator opens the secondary control valve 21. This secondary control valve may be opened and closed as many times as the operator desires in his manipulation of the hose line.

When the fire is extinguished and the hose line 14 is again wound up on the reel 11, the operator will return the nozzle 20 and the "play-pipe" 19 to their supporting platform or shelf 22 and the holding mechanism 23 will be manipulated to

fasten the nozzle and "play-pipe" in place against accidental or unintentional removal. This manipulation of the holding mechanism 23 to secure the discharge nozzle will bring about operation of the pilot valve 24 for reestablishing communication between the supply tubing 25 and the delivery tubing 26 and for disconnecting the latter tubing from the atmosphere.

Although this fire extinguishing apparatus is primarily intended for use with such an extinguishing medium as carbon dioxide, it is to be understood that the apparatus may be employed for discharging other extinguishing substances, such as water. When this apparatus is employed for discharging carbon dioxide, the supply tubing 25 is preferably connected to the vapor space of the carbon dioxide storage means. If the discharge apparatus is employed for controlling the release of some other fire extinguishing medium, maintained under relatively high pressure, the supply tubing 25 will be connected to the high pressure liquid supply, or some other fluid pressure medium.

Although the hose line 14 is illustrated as being wound on the reel 11, it is to be understood that other conventional types of hose supports or carriers may be employed if desired. Without intending in any way to limit the application or use of this extinguishing apparatus, it will be noted that Figs. 1 and 2 illustrate the apparatus as being associated with a mobile fire fighting unit. The mounts 10 for the hose reel are specifically illustrated in Fig. 1 as being supported by the side chassis bar 27 of such a mobile unit while the nozzle supporting platform or shelf 22 specifically takes the form of the step or running board of the mobile unit. It readily will be appreciated, however, that this discharge apparatus can just as well be mounted on the rear end of a mobile unit or even associated with a vertical wall or column of a building.

The detail structural features of the various instrumentalities which are generally illustrated in Figs. 1 and 2 are shown in the remaining figures of the drawings. These remaining figures now will be employed in presenting detailed descriptions of the said instrumentalities.

Fig. 6 illustrates the details of the main control valve 17. This control valve includes the main body portion 28 with its inlet 29 and outlet 30. A partition 31 separates the inlet and the outlet of the valve body and is provided with an opening 32 that is surrounded by the valve seat 33.

On the inlet side of the partition 31, the valve body is provided with an internally threaded opening 34 that is adapted to receive and be threadedly connected to the cap 35. A sealing gasket 36 functions to prevent leakage between the valve body 28 and the cap 35. This cap is of hollow construction to provide an internal cylinder 37 to receive the combined piston and valve body 38 and to form a pressure chamber 39 above the piston portion of the element 38. The cap is further provided with an internally threaded opening 40 for connection with the outer end of the fluid delivery tubing 26, see Figs. 1 and 2. The cap is further provided with a depression or recess 41 that functions to seat the upper end of the valve body loading spring 42.

The lower portion of the combined piston and valve body member 38 is provided with a suitable seating disc 43 which is adapted to engage the valve seat 33 when the valve is closed. This seating disc is held in place by the retainer 44

that is secured to the combined piston and valve body 38 by the threaded stem and nut assembly 45.

The said body 38 is recessed at 46 to accommodate the lower portion of the loading spring 42.

The upper portion of the combined piston and valve body 38 is reduced in diameter to accommodate the cup leather 47 that is reinforced or backed up by the resilient expander 48. This expander includes a plurality of curved spring fingers which underlie the cylinder wall engaging portion of the cup leather 47. Overlying the secured portion of the cup leather is a retaining ring 49 while a resilient shock absorber and sealing ring 50 overlies the retainer ring. These various packing elements 47 to 50 inclusive are secured to the combined piston and valve body 38 by a suitable number of screws 51.

When this valve is properly connected up to control the flow of the high pressure extinguishing medium to the hose line 14, the liquid carbon dioxide, or the like, fills the portion of the valve body 28 above the partition 31, or on the inlet side of this partition. The exposed lower portion of the combined piston and valve body 38, therefore, is subjected to this fluid pressure.

The supply and delivery tubes 25 and 26 apply carbon dioxide vapor pressure to the upper surfaces of the body 38 as a result of the development of the vapor pressure in the chamber 39. This vapor pressure, which is equal to the liquid pressure in the inlet portion of the valve body 28, plus the load imposed upon the combined piston and valve body 38, hold the seating disc 43 of the valve tightly engaging the seat 33. When the pilot valve 24 is actuated to vent the delivery tubing 26 to the atmosphere, the pressure in the pressure chamber 39 is relieved and the combined piston and valve body 38 is then only loaded by the spring 42. The liquid pressure applied to the exposed bottom face of the valve body 38 will then be greater than the force of the spring 42 and this fluid pressure will cause the valve to be unseated to permit flow of liquid carbon dioxide from the inlet end 29 to the outlet end 30 of the valve body 28. When the pilot valve is again operated to interconnect the supply tubing 25 and the delivery tubing 26 and to close off the opening to the atmosphere, vapor pressure will again develop in the pressure chamber 39.

When the vapor pressure in chamber 39 equals the pressure in the inlet of the valve body 28, the combined piston and valve body 38 will be moved by the spring 42 to place the seating disc 43 in sealing engagement with the seat 33.

The pilot valve structure is illustrated in Figs. 7 and 8. This pilot valve includes a body portion 52 which is provided with a pair of mounting apertured ears 53. This valve body is provided with a chamber 54 that communicates with a reduced extension 55 having a venting port 56 formed therein by means of which the chamber extension 55 may discharge to the atmosphere. An annular valve seat 57 surrounds the area of communication between the chamber 54 and the reduced chamber extension 55.

A lateral connection opening 58 is formed in the pilot valve body 52 for connection with the end of the fluid pressure delivery tubing 26. In other words, this pilot valve opening 58 is placed in communication with the opening 40 in the cap of the main control valve, see Fig. 6, by means of the pressure delivery tubing 26.

The pilot valve body chamber 54 is internally screw threaded at its open end 59 for connec-

tion with or to receive the reduced end portion 60 of the cap 61. This cap is formed with an opening 62 which is internally screw threaded for connection with the end of the delivery tubing 25 that extends from the source of supply of the fluid pressure. The cap 61 is additionally bored at 63 for communication with the chamber 54 of the pilot valve body 52. A valve seat 64 seat surrounds the inner end of the bored portion 63 of the cap.

A double ended plunger 65 is located in the chamber 54 of the pilot valve body 52 and is adapted to alternately engage the valve seats 57 and 64. A spring 66 normally functions to cause the plunger 65 to engage the valve seat 57. A plunger rod 67 projects from the mounting end of the pilot valve body 52. When proper force is applied to this plunger stem 67, the spring 66 will be overcome and the plunger will be moved out of engagement with the seat 57 and into engagement with the seat 64.

Fig. 8 discloses the plunger body in its normal position. When in this position, the supply tubing 25 is placed in communication with the delivery tubing 26 so that fluid pressure will pass through the pilot valve body 52 from the source of supply to the pressure chamber 39 of the main control valve 17. Seating of the plunger 65 against the annular seat 57 closes off the chamber 54 from the vent port or opening 56. When the plunger 65 is moved into engagement with the annular seat 64, the supply tubing 25 is disconnected from the delivery tubing 26 and the fluid pressure developed in the chamber 39 of the main control valve 17 is vented through the tubing 26 into the chamber 54 of the pilot valve body and from this chamber into the chamber extension 55 and then through the port 56 to the atmosphere.

Figs. 3 and 4 disclose the holding mechanism for the "play-pipe" 19 and the discharge nozzle 20. This holding mechanism 23 includes a bracket 68 that is suitably secured at its inner end 69 to any appropriate support 70. Figs. 1 and 2 disclose this support 70 as being the inner guard plate for the step or running board 22. The outer end of the bracket 68 is notched at 71 to receive the "play-pipe" 19. A combined locking plate and pilot valve operating handle 72 is secured at 73 to the rock shaft 74 that extends lengthwise through the bracket 68. A stop or keeper 75 is secured to the outer end of the bracket 68 on the opposite side of the notch 71. When the combined locking plate and handle 72 is in the full line position of Figs. 3 and 4, the "play-pipe" receiving notch 71 is uncovered and the "play-pipe" may be moved into and out of the same. When the locking plate and handle 72 is swung into a position where it will engage the keeper or stop plate 75, the entrance to the notch 71 will be closed and the "play-pipe" 19 will be locked or held therein.

The rock shaft 74 projects beyond the support 70 at the inner end of the bracket 68. Secured to the inner projecting end of this rock shaft is a rocker arm 76. This rocker arm is illustrated in Fig. 3 as having an over-travel, spring pressed, relief plunger 77 mounted in a recess 78 thereof. The pilot valve 24 is illustrated in Figs. 3 and 4 as being supported on the mounting member 70 in such a manner as to have the plunger 77 line up with and engage the plunger stem 67 thereof when the combined locking plate and handle 72 is arranged in its unlocking or

"play-pipe" releasing position. This position is shown in full lines in Figs. 3 and 4.

The rocker arm 76 is provided with a pin or post 79. This pin or post is carried by the free end portion of the rocker arm 76. A snap spring 80 is connected to this pin or post 79 at one end and to a fixed pin or post 81 at its other end. It will be seen that this snap spring 80 will function to load the rocker arm 76 so that its over-travel relief plunger 77 will engage the pilot valve plunger stem 67 and will apply sufficient force to the latter to move the pilot valve plunger 65 off of its seat 57 into engagement with its seat 64. Therefore, when the combined locking plate and handle 72 is moved into the full line position illustrated in Figs. 3 and 4, the "play-pipe" 19 is released and the pilot valve 24 is operated for venting the pressure chamber 39 of the main control valve 17 to the atmosphere. Due to the spring mounting of the relief plunger 77 of the rocker arm 76, the snap spring 80 will be prevented from applying sufficient force to the pilot plunger 65 to damage the same when it engages the seat 64.

Fig. 3 illustrates the combined locking plate and handle 72, by means of dot and dash lines, in its intermediate position where the snap spring connected pin or post 79 is on a dead center with the rock shaft 74, which mounts the rocker arm 76, and the fixed pin or post 81 of the spring 80. When this spring connecting pin or post 79 moves past this dead center position in either direction, the tension of the snap spring 80 will function to move the combined locking plate and handle 72 into one of its extreme positions; i. e., either into its locking position in engagement with the keeper or stop 75 or into its pilot valve operating position as is shown in full lines in Figs. 3 and 4. Therefore, the operator who actuates the combined locking plate and handle 72 for either releasing or securing the "play-pipe" 19 is not relied upon to move the member 72 fully into either of its extreme positions.

The manual "play-pipe" valve 21 is illustrated in detail in Fig. 5. This valve includes a body 82 that has an inlet end 83 and an outlet end 84. A partition 85 separates the inlet and outlet portions of the interior of the valve body. This partition is provided with an opening 86 that is surrounded at one side by the valve seat 87. The valve body 82 is shaped on the inlet side of the partition 85 so as to form a cylinder 88 in which is movably mounted the combined valve and piston body 89. A removable cap 90 is employed for closing the outer end of the cylinder 88. This cap is held in place by means of the clamping ring or nut 91 which is threadedly connected to the valve body cylinder portion 88.

The valve portion of the combined valve and piston body 89 is provided with a seating ring 92 that is adapted to engage the seat 87 of the partition 85. A ribbed nut 93 is employed for holding the seating ring or disc 92 in place on the body 89 and also functions to guide the movements of the combined valve and piston body 89 by engaging the wall of the partition opening 86. The ribbed construction of this nut 93 allows for the passage of the controlled fluid as soon as the seating disc or ring 92 has been moved away from the partition seat 87.

The piston portion of the combined valve and piston body 89 is formed with an annular recess or pocket 94 that opens through the end of the body 89 and functions to receive the adjacent end portion of the spring 95. The remaining

end of this spring bears against the removable cap 90. A small port 96 is formed in the piston portion of the combined valve and piston body 89 and functions to place the pressure chamber 97 in open communication with the inlet side of the valve body 82. It will be seen, therefore, that the fluid pressure developed in the cylinder chamber 97, as a result of flow of fluid from the inlet "play-pipe" section, and the spring 95 will maintain the ring or disc 92 in engagement with the partition seat 87 when the valve is closed.

The combined valve and piston body 89 is formed with an axial passage 98 which accommodates the body or stem of the pilot valve 99. This pilot valve is formed with a head 100 which is adapted to seat at one end of the passage 98. A spring 101 normally retains this pilot valve head 100 seated.

An operating plunger 102 engages the upper end of the pilot valve body 99. This plunger is provided with a stem 103 that projects out of the valve body or casing 82 through the packing gland assembly 104. An operating lever 105 is pivoted at 106 to a supporting bracket 107 carried by the valve body or casing 82. A slotted lever guide 108 is attached to the valve body or casing 82 and allows for movement of the pilot valve operating lever 105 between its two extreme positions, as illustrated in Fig. 5. The handle or grip portion 109 of the pilot valve operating lever 105 is so angularly arranged that it will flatly bear against the "play-pipe" 19 when moved into its dot and dash line position. When in this position, the secondary control valve 21 will be open to allow the fire extinguishing fluid to flow through the "play-pipe" to the discharge nozzle 20.

The operation of this "play-pipe" control valve will now be explained.

It was pointed out above that the bleeder port 96, formed in the piston portion of the body 89, will allow fluid pressure to develop in the cylinder pressure chamber 97 and this fluid pressure plus the spring 95 will maintain the seating disc or ring 92 in engagement with the partition seat 87. When the operator desires to open this "play-pipe," or secondary control, valve the operating lever 105 is moved from its full line position into its dot and dash line position. This pivotal movement of the lever will depress the plunger 102 and cause the pilot valve head 100 to be unseated against the pressure of its spring 101. Unseating of the pilot valve results in emptying the fluid from the pressure chamber 97 at a more rapid rate than it can be developed as a result of flow of fluid through the vent opening or port 96. The pressure in the chamber 97 then drops to such a value that the fluid pressure in the inlet side of the valve casing or body 82 will force the main valve away from the partition seat 87 to permit the fluid to flow through the partition opening 86. When the operator desires to close this valve 21, the lever 105 is released and the spring 101 returns the pilot valve head 100 to its seat to close the discharge port or passage 98 formed in the combined valve and piston body 89. Fluid pressure then builds up in the pressure chamber 97 and when this fluid pressure equals the fluid pressure in the inlet side of the valve casing 82 the spring 95 will move the seating disc or ring 92 into engagement with the partition seat 87.

To briefly review the entire fire extinguishing mechanism, it will be seen that an operator will not be allowed to release the discharge nozzle 20

and its "play-pipe" 19 from the holding means 23 and pull the hose line 14 off of its supporting reel 11 without effecting operation of the main control valve 17 so that the extinguishing medium 5 will fill the hose line 14. However, the extinguishing medium will not be discharged through the nozzle 20 as a result of opening the main control valve 17. This discharge of the extinguishing fluid will only result from manual 10 operation of the control lever 105 for the secondary or "play-pipe" control valve 21. This secondary or "play-pipe" control valve additionally 15 will only remain open so long as the operator retains the handle portion 109 of the lever 105 in its depressed position. Therefore, if the operator releases his hold on the "play-pipe" 19 and the lever 105 of the secondary control valve, this valve will close and the extinguishing medium 20 will not be discharged from the nozzle 20 to cause the end of the hose line to whip and thrash around in such a violent manner as to cause severe injury to anyone trying to recapture the same.

It is to be understood that the form of this 25 invention herewith shown and described is to be taken as the preferred example of the same, and that various changes in the shape, size, and arrangement of parts may be resorted to without departing from the spirit of the invention or the 30 scope of the subjoined claims.

Having thus described the invention, I claim:

1. Fire extinguisher discharge apparatus comprising a supply pipe for the extinguisher medium, a control valve in said supply pipe, a hose line, having a discharge device at its outer end, connected to the supply pipe, means for releasably supporting and holding the discharge device, including a member movable into discharge device releasing and securing positions, means operatively connected to the movable member for assuring full movement of said member into and for holding it in its discharge device releasing and securing positions, and means actuated by 40 said movements of the movable member for effecting opening and closing operations of the control valve.

2. Fire extinguisher discharge apparatus comprising a supply pipe for the extinguisher medium, a differential fluid pressure operated control valve in said supply pipe, a hose line, having a discharge device at its outer end, connected to the supply pipe, means for releasably supporting and holding the discharge device, and means actuated by operation of the holding portion of 50 the first mentioned means, in releasing and securing the discharge device, for effecting opening and closing operations, respectively, of the control valve by properly changing the differential pressure condition of the control valve.

3. Fire extinguisher discharge apparatus comprising a supply pipe for the extinguisher medium, a differential fluid pressure operated control valve in said supply pipe, a hose line, having a discharge device at its outer end, connected to the supply pipe, means for releasably supporting and holding the discharge device including a member movable into discharge device releasing and securing positions, and means actuated by 55 said movements of the movable member for effecting opening and closing operations of the control valve by properly changing the differential pressure condition of the control valve.

4. Fire extinguisher discharge apparatus comprising a supply pipe for the extinguisher me-

dium, a differential fluid pressure operated control valve in said supply pipe, a hose line, having a discharge device at its outer end, connected to the supply pipe, means for releasably supporting and holding the discharge device, and a pilot valve actuated by operation of the holding portion of the first mentioned means, in releasing and securing the discharge device, for effecting operation of the control valve by properly changing the differential pressure condition of the control valve.

5. Fire extinguisher discharge apparatus comprising a supply pipe for the extinguisher medium, a differential fluid pressure operated control valve in said supply pipe, a hose line, having a discharge device at its outer end, connected to the supply pipe, means for releasably supporting and holding the discharge device including a member movable into discharge device releasing and securing positions, and means actuated by operation of the holding portion of the first mentioned means, in releasing and securing the discharge device, for effecting opening and closing operations, respectively, of the control valve by properly changing the differential pressure condition of the control valve.

10. 6. Fire extinguisher discharge apparatus comprising a supply pipe for the extinguisher medium, a control valve in said supply pipe, a hose line, having a discharge device at its outer end, connected to the supply pipe, means for releasably supporting and holding the discharge device including a member movable into discharge device releasing and securing positions, a spring device adapted to snap past its dead center position in either direction for assuring full movement of the said movable member into and for holding it in its discharge device releasing and securing positions, and means actuated by said movements of the movable member for effecting opening and closing operations of the control valve.

15. 7. Fire extinguisher discharge apparatus comprising a supply pipe for the extinguisher medium, a differential fluid pressure operated control valve in said supply pipe, a hose line, having a discharge device at its outer end, connected to the supply pipe, means for releasably supporting and holding the discharge device including a member movable into discharge device releasing and securing positions, a spring device adapted to snap past its dead center position in either direction for assuring full movement of said movable member into and for holding it in its discharge device releasing and securing positions, and means actuated by said movements of the movable member for effecting opening and closing operations of the control valve by properly changing the differential pressure condition of the control valve.

20. 8. Fire extinguisher discharge apparatus comprising a supply pipe for the extinguisher medium, a differential fluid pressure operated control valve in said supply pipe, a hose line, having a discharge device at its outer end, connected to the supply pipe, means for releasably supporting and holding the discharge device including a member movable into discharge device releasing and securing positions, a spring device adapt-

ed to snap past its dead center position in either direction for assuring full movement of the said movable member into and for holding it in its discharge device releasing and securing positions, and a pilot valve actuated by operation of the movable member, in releasing and securing the discharge device, for effecting operation of the control valve by properly changing the differential pressure condition of the control valve.

25. 9. Fire extinguisher discharge apparatus comprising a fixed supply pipe for the extinguisher medium, a control valve in said supply pipe, a discharge nozzle, means for connecting the discharge nozzle to the fixed supply pipe to permit the nozzle to be moved from a non-fire extinguishing position to a fire extinguishing position, means for releasably holding the nozzle in its non-fire extinguishing position including a pivoted locking plate movable into releasing and securing positions, and means actuated by said movements of the pivoted locking plate into its releasing and securing positions for effecting opening and closing operations, respectively, of the control valve.

30. 10. Fire extinguisher discharge apparatus comprising a fixed supply pipe for the extinguisher medium, a fluid pressure operated control valve in said supply pipe, a discharge nozzle, means for connecting the discharge nozzle to the fixed supply pipe to permit the nozzle to be moved from a non-fire extinguishing position to a fire extinguishing position, means for releasably holding the nozzle in its non-fire extinguishing position, and fluid pressure flow controlling means actuated by operation of the holding means, in releasing and securing the discharge nozzle, for effecting opening and closing operations, respectively, of the control valve.

35. 11. Fire extinguisher discharge apparatus comprising a fixed supply pipe for the extinguisher medium, a fluid pressure operated control valve in said supply pipe, a discharge nozzle, means for connecting the discharge nozzle to the fixed supply pipe to permit the nozzle to be moved from a non-fire extinguishing position to a fire extinguishing position, means for releasably holding the nozzle in its non-fire extinguishing position, and a fluid pressure flow controlling pilot valve actuated by operation of the holding means for the nozzle, in releasing and securing the nozzle, for effecting opening and closing operations of the control valve.

40. 12. Fire extinguisher discharge apparatus comprising a supply pipe for the extinguisher medium, a control valve in said supply pipe, a reel having its shaft connected to the supply pipe, a hose line adapted to be wound on the reel and having its inner end connected to the reel shaft, a "play-pipe" having a discharge nozzle at its outer end connected to the outer end of the hose line, a support for the "play-pipe" and discharge nozzle independent of the hose reel, a pivoted locking plate for releasably securing the "play-pipe" and discharge nozzle to the support, and means operated by actuation of the said pivoted locking plate for effecting opening and closing of the control valve.

HILDING V. WILLIAMSON.
